METHOD OF AND MACHINE FOR FITTING SOLES

Louis Servonnat, Veiron, Chemin des Villas, France, assignor to United Shoe Machinery Corporation, Paterson, N. J., a corporation of New Jersey

Application November 7, 1932, Serial No. 641,587
In France November 14, 1931

5 Claims. (Cl. 12—27)

This invention relates to improvements in methods of fitting soles and to improvements in sole fitting machines and is herein illustrated with reference to the channeling of orthopedic insoles.

- 5 Orthopedic insoles, so-called, commonly have lateral extensions or "wings" at opposite sides or sometimes at one side only of their shank portions and in the manufacture of shoes having such insoles the extensions or wings are laid back or 10 molded against the sides of the lasts so that they will serve in the finished shoes to afford supports for the instep arches of the feet. In channeling such an insole to prepare it for attachment to a shoe the channel or channels should extend parallel to the sole edge around the forepart of the insole where the insole has a normal outline but at the shank portion of the insole the channels, instead of following the outline of the wings, should extend across the base of each wing, following the same course as if the insole was of 15 normal marginal contour in the shank portion. For this reason it is impracticable to control the movement of an orthopedic insole past a channeling knife or knives by the engagement of an edge gage with the edge of the insole in the manner customary in channeling normal insoles, inasmuch as such a method would result in getting the channel parallel to the edges of the wings. Accordingly, it has been customary heretofore in 20 some instances to channel such orthopedic insoles in two separate operations, in one of which the location of the channel at the forepart of the insole has been determined by the engagement of an edge gage with the sole edge, and in the other of which the location of the channel along the 25 base of the wing has been gaged by the eye of the operator. In other instances it has been found practicable to channel an orthopedic insole in a single continuing operation in a channeling machine by employing a displaceable edge gage, shifting the gage into an inoperative position at the wing or wings of the insole, and continuing the channeling while guiding the insole by eye, sometimes with the aid of a line drawn upon the 30 surface of the insole.

One object of the present invention is to provide an improved method of channeling or otherwise fitting orthopedic insoles or insoles having abnormal marginal contours which will insure positive gaging of the location of the channel or other fitting at the wings or other portions where the sole is abnormal in outline.

With this object in view, the invention in one aspect contemplates an improved method of fitting soles such, for example, as orthopedic insoles

which are abnormal in the shank portions but which are normal in other portions and wherein the abnormality consists in the presence of a wing extending laterally on each side of the shank beyond the outline of a normal shank, which method preferably consists in affixing to one side of such a sole a templet having an outline corresponding to that of a normal sole, the normal portion of the outline of the sole registering with the corresponding portion of the outline of the templet and the opposite lateral edges of the templet extending across the bases of the wings of the sole along lines corresponding to the edges of a normal sole shank portion and utilizing the templet in guiding relative movement between the sole and a channeling or other sole fitting tool to enable the tool to operate upon the sole along a line determined by the outline of the templet.

As herein exemplified with reference to the channeling of orthopedic insoles a templet is secured in place upon an insole with the edge of the forepart of the templet registering with the edge of the forepart of the insole. The shank portion of the templet will then be so positioned that its opposite lateral edges extend across the bases of the wings of the insole along lines corresponding to the edges of a normal insole shank portion. The insole with the attached templet may then be fed past the channeling knives of a channeling machine having an edge gage capable of guiding the sole by engagement with the edge of the templet, not only during operations upon the forepart of the insole but also while the wings of the insole are being operated upon.

The present invention, considered in another aspect, and with reference to a preferred embodiment illustrated herein, is concerned also with the provision, in combination with sole fitting means and a work table and means for feeding to the sole fitting means an orthopedic insole with an attached templet having an outline corresponding to that of a normal sole and beyond which extends a wing of the insole, of an edge gage having its work engaging surface formed at the free extremity of a thin elongated finger, the finger being 45 constructed and arranged to extend between the extending wing of the insole and the work table to cooperate with the edge of the templet to guide the insole as it is being fed. The illustrated edge gage is mounted for adjustment transversely of the direction of work feed, and means is provided in the illustrated machine for adjusting the gage to vary the location of the channel or channels in a direction or directions edgewise of the sole at different parts of the sole.

The invention will be explained with reference to the accompanying drawing, in which

Fig. 1 is a plan view of a channeled orthopedic insole having a templet attached thereto for use in controlling the channeling operation, the figure showing also an edge gage of improved construction in operative relation to the templet;

Fig. 2 is a sectional view of the insole and templet shown in Fig. 1, the section being taken 10 along the line II—II of Fig. 1 and the figure showing also, in elevation and in operative relation to the work, the edge gage, the work table, the feed foot, and the channeling knives of a channeling machine of a type suitable for use in channeling 15 an insole; and

Fig. 3 is a sectional view of the edge gage and its adjusting means, the section being taken along the line III—III of Fig. 2.

Referring to the drawing, there is shown at 6 an orthopedic insole having a forepart 8 of normal outline and a shank portion 10 of abnormal outline due to the presence at both its inner and outer sides of lateral extensions or wings 12 which are adapted to be bent upwardly from the plane 25 of the sole and to lie inside the upper of the shoe to afford support for the instep arch of the foot. The insole 6 is shown as having been fitted for attachment to a shoe upper by the provision of an outer channel 14 and an inner channel 16. 30 For use in channeling the insole a templet 18 is shown as being attached to the grain side of the insole by means of tacks 20, although any other suitable means of attachment may be employed.

The templet 18 has a forepart 22, the outline 35 of which corresponds to that of the forepart of the insole 6, and a shank portion 24, the outline of which corresponds to that of the shank portion of a normal insole. As shown, the templet is positioned upon the insole with the edge of the forepart of the templet registering with the edge of the forepart of the insole while the edge of the shank portion of the templet extends along lines spaced inwardly from the edges of the wings and following the lines of a normal shank.

45 After an insole has been prepared by having the templet secured thereto as above described the insole, with the attached templet, is presented to a channeling machine in which provision is made for guiding the insole by the engagement of an edge gage with the edge of the templet. As shown in Fig. 2 of the drawing, the machine is provided with a work table 28, a feed foot 30, an inner channeling knife 32, an outer channeling knife 34, and an edge gage 36. The 50 feed foot functions in a well-known manner to feed the work (which in this case comprises both the insole and the templet) over the work table 28 and past the knives 32 and 34. In order that it may guide the sole by engagement with the 55 edge of the templet the illustrated edge gage 36 is made in the form of an elongated finger which is arranged to extend in the plane of the templet, the thickness of the gage finger corresponding to the thickness of the templet and the length of the 60 gage finger being such as to insure that the finger will extend beneath the wings of the insole and above the work table in the engagement with the edge of the shank portion of the templet. As shown, also, the edge gage finger 36 is carried by a slide 38 which is mounted for movement 65 in a direction transverse to the direction of feed of the sole and the slide 38 is provided with rack teeth 40 adapted to be engaged by means such, for example, as the segmental gear 42 shown in 70 Fig. 3 and other suitable manually operated

mechanism (not shown) whereby the gage slide 38 may be shifted to adjust the gage 36 while the machine is running and thus to shift the insole relatively to the knives in a direction widthwise of the channels to vary the location of the 5 channels relatively to the edge of the templet.

In channeling an orthopedic insole in accordance with the improved method of the present invention as herein exemplified, the insole with the templet secured thereto in the relation above 10 specified is laid, templet side down, upon the work table 28 with the edge of the templet at one side of its shank portion against the edge gage 36.

The sole is then fed across the table by the 15 action of the feed foot 30 so that the margin of the insole is advanced past the knives 32 and 34 which operate to form the inner and outer channels 16 and 14 respectively. Inasmuch as the sole is guided by the engagement of the edge gage 36 20 with the templet 18 the channels will be cut parallel to the edge of the sole around the forepart where the outline of the sole corresponds to that of the templet. In the shank portion of the insole, however, where the outline of the 25 templet does not correspond to the outline of the insole but follows the lines of the shank edges of a normal insole, the channels in the insole will follow the edge of the templet and cut across the bases of the wings 12 instead of 30 extending parallel to the edges of the wings. Obviously, the templet can readily be detached from the sole after the latter has been channelled, it being necessary only to pull them apart thus to dislodge the tacks 20 from the insole. 35

Having described my invention, what I claim as new and desire to secure by Letters Patent of the United States is:

1. That improvement in methods of fitting soles having outlines which are abnormal in the 40 shank portions but which are normal in the other portions of the soles, and wherein the abnormality consists in the presence of a wing extending laterally on each side of the shank beyond the outline of a normal shank, which consists 45 in laying upon a sole of the type specified a templet having an outline corresponding to that of a normal sole, relatively adjusting the templet and the sole with the normal portion of the outline of the sole registering with the corresponding portion of the outline of the templet and with the opposite lateral edges of the templet extending across the bases of the wings of the sole along lines corresponding to the edges of a normal sole shank portion, securing together the templet and the sole in said position of relative adjustment, and utilizing the templet in guiding relative movement between the sole and a sole-fitting tool to enable the latter to operate upon the sole along a line determined by the outline of the 50 templet. 55

2. That improvement in methods of channeling orthopedic insoles which consists in laying upon an orthopedic insole a templet having an outline corresponding to that of a normal insole and relatively adjusting the insole and the templet with the normal portion of the outline of the insole registering with the corresponding portion of the outline of the templet, securing together the templet and the insole in said position of relative adjustment, and feeding the insole, together with the templet, through a channeling machine while utilizing the templet in conjunction with an edge gage to guide the insole as it is being fed to cause the channel to extend parallel to the edge 70 75 75

of the insole at the forepart but not along the shank portion of the insole.

3. In a machine for fitting orthopedic insoles having lateral arch supporting extensions at their shank portions, insole fitting means, a work table, a templet having the outline of a normal insole and having a flat surface adapted for attachment to a face of an orthopedic insole with a lateral wing of the insole extending beyond the edge of the templet, said templet having also an oppositely disposed surface adapted to engage said work table, means for feeding to said fitting means the orthopedic insole with the attached templet, and an edge gage having its work-engaging surface formed at the free extremity of a thin elongated finger constructed and arranged to extend between said work table and said extending lateral wing at the shank of the insole to cooperate with the edge of the templet on the insole 20 to guide the insole as it is being fed.

4. In a machine for channeling orthopedic insoles having lateral arch supporting extensions at their shank portions, a channeling knife, a work table, a templet having the outline of a normal insole and having a flat surface adapted for attachment to a face of an orthopedic insole with a lateral wing of the insole extending beyond the edge of the templet, said templet having also an oppositely disposed surface adapted to engage said work table, means for feeding to the said knife the orthopedic insole with the attached templet, an edge gage having its work-engaging surface formed at the free extremity of a thin

elongated finger constructed and arranged to extend between said work table and said extending lateral wing at the shank of the insole to cooperate with the edge of the templet to guide the insole as it is being fed, and means for adjusting the edge gage transversely of the line of feed of the insole to vary the location of the channel widthwise relatively to the edge of the templet.

5. In a machine for channeling orthopedic insoles having lateral arch supporting extensions in their shank portions, a work table, a templet having an outline corresponding to that of a normal insole and adapted to be secured to the face of the insole with the edge of the forepart of the templet registering with the edge of the forepart of the insole and with the edge of the shank portion of the templet spaced inwardly from the edges of the lateral extensions of the insole, a channeling knife, means for feeding the insole and the templet to the knife, and an edge gage having its work-engaging surface formed at the extremity of a finger elongated in a plane parallel to the face of the work table, the thickness of said finger corresponding to the thickness of the templet and the finger being adapted to extend 25 into the narrow space between the work table and the lateral extension of the insole where the latter is spaced away from the work table by the templet to enable the edge gage to engage the edge of the shank portion of the templet to 30 guide the insole as it is being fed.

LOUIS SERVONNAT.
